Harry C. Jones, New York, N. Y.

Application December 5, 1933, Serial No. 700,989

18 Claims. (Cl. 95—76)

This invention relates to apparatus for printing a light sensitive surface through a sheet of transparent material, and particularly, to photographic contact printing apparatus.

5 My invention is adapted for application to a wide variety of contact printing apparatus, regardless of how contact between the negative and the sensitized surface is attained, and contemplates the provision of efficient and comparatively 10 low cost printing means.

My invention further contemplates the provision of lever means for manipulating the movable parts of printing means which require more than a trifling amount of power to effect the 15 desired movement.

20 My invention further contemplates the provision of economical means for supporting the flexible material or blanket of the printing means to prevent side motion of the blanket when the two holding frames usually employed in contact printing are put together.

25 My invention further contemplates the provision of contact printing means employing a pair of interchangeable holding frames, and of means for so supporting and manipulating the frames as to interchange their relation quickly, easily, economically and efficiently.

30 My invention further contemplates the provision of cushioning means for preventing shocks and jarring when the holding frames are manipulated.

35 The various objects of my invention will be clear from the description which follows and from the drawings, in which,

Fig. 1 is a side elevation of my new apparatus. Fig. 2 is a front elevation thereof.

Fig. 3 is a side elevation on an enlarged scale of the left end of the frame manipulating lever showing the means for supporting and connecting 40 the upper ends of the holding frame operating cables.

Fig. 4 is a top plan of my new apparatus.

Fig. 5 is a vertical section of the same, taken on the line 5—5 of Fig. 2.

45 Fig. 6 is a cross section of the manipulating lever taken on the line 6—6 of Fig. 2.

Fig. 7 is a fragmentary vertical section taken on the line 7—7 of Fig. 8 of the blanket-carrying holding frame.

50 Fig. 8 is a plan view of the same, the blanket being shown partly broken away to expose the blanket supporting structure.

Fig. 9 is a section taken on line 9—9 of Fig. 10 and similar to Fig. 7, of a modified form of the 55 blanket supporting means.

Fig. 10 is a plan view of the same similar to Fig. 8.

Fig. 11 is a fragmentary vertical section of the means for locking the lower holding frame, taken on the line 11—11 of Fig. 1.

Fig. 12 is a side elevation similar to Fig. 1 of a modified form of my new apparatus.

Fig. 13 is a front elevation of the same.

Fig. 14 is a similar fragmentary view of a modified form of the lever operating means.

Fig. 15 is a similar view of another modified form of the same.

Fig. 16 is a front elevation of one of the chain sprocket wheels of Fig. 13 showing the chain secured thereto.

15 In that practical embodiment of my invention which I have shown by way of example, my new apparatus comprises generally, a pair of interchangeable holding frames and means for easily manipulating whichever frame is arranged uppermost.

20 Said frames are usually movable relatively to each other to permit the insertion of the negative and of the sensitized surface on or into one or the other of the frames. One of the frames is 25 adapted to carry a blanket and the other frame is adapted usually to carry a glass. Where contact between the negative and the sensitized surface is produced by vacuum, the frames are provided with means for sealing the frames together 30 and particularly, for sealing the space between the glass and the blanket and thereby permitting the blanket when under vacuum suction, to force the sensitized surface into intimate contact with the negative which is backed by the glass.

35 Since for different types of work, vacuum printing frames are sometimes used with the glass uppermost and the blanket below the glass, and at other times with the glass below the blanket, means are provided for manipulating that frame 40 which happens to be uppermost, and for interchanging the frames to reverse the positions thereof when desired. I have also provided means for so holding the blanket as not to detract materially from the flexibility thereof while at the 45 same time supporting the blanket in such a manner that any danger of the blanket causing relative movement of the negative and the sensitized surface is prevented. The frames above described being of such large size that they are 50 quite heavy, they cannot be directly manipulated manually, but require manipulating and supporting means so that the frames may be brought together and separated when desired.

With the above in mind, the description of the 55

particular means which I have illustrated for carrying out the various aims of my invention may proceed.

Referring to Figs. 1 and 2 particularly, a pair of frames 20 and 21 are separately supported. I will refer to said frames hereinafter as the "holding frames" to distinguish the holding frames from the entire apparatus which is commonly known as a printing frame. The lower frame 20 may be either a blanket holding frame or a glass holding frame, the upper frame 21 holding the glass if the lower frame is the blanket holder, or holding the blanket if the lower frame is the glass holder. In any case, the lower frame is pivotally supported upon the standards 22 as by means of the brackets 23, each located at one of the ends of the lower frame and each pivoted to the adjacent standard by a suitable pin 24. The flange 25 of the bracket 23 is of sufficient height to extend substantially as far above the upper surface of the lower holding frame as it extends below said surface. Said flange is removably secured to the lower holding frame in any suitable manner as by means of the bolts 26 or screws 26. A suitable bracket as 27, removably secured to the standard 22 is provided with a stop 28, (Figs. 1, 2, 11), adapted to engage the under surface of the lower holding frame to maintain said frame in the horizontal position 30 into which it is swung about the pins 24. The pin 29 on said bracket 27 is adapted to removably engage an end of the lower holding frame to lock said frame in its horizontal position when desired, said pin being removable to permit swinging of 35 the frame into upright position, in which position the lower holding frame engages the removable stop 30 arranged on the foot of the standard 22.

The upper holding frame 21 is supported in 40 horizontal position by means of a pair of frame supports 31, each of which is adjustably carried by a slide 32. The frame support is provided with a pair of arms 33 diverging upwardly and each terminating in a semi-cylindrical recess 34. 45 A pin 35 projecting from the end of the frame is inserted into each of the recesses 34 whereby the upper holding frame is supported by the frame support until said frame support is withdrawn from the pins 35.

50 As will be later explained in more detail, it sometimes becomes advisable to adjust the frame support relatively to the slide 32. I therefore prefer to connect said support to the slide by wing screws as 36 cooperating with a selected one of the series of holes 37 in the slide 32. Said slide is mounted for longitudinal movement upwardly and downwardly on the standard 22 when the upper holding frame is to be moved in the corresponding direction.

60 It will be understood that the slide moves downwardly past the pivot pins 24 of the lower holding frame when it is desired to secure said frames together. Toward this end, the slide 32 embraces the standard 22 on three sides, being held in place 65 by suitable narrow gibs 38 (Fig. 4) engaging the fourth side of the standards. It will be understood that where the standards are round instead of square in cross-section, the slide 32 is of corresponding shape and suitably embraces the standard 22 for slidable movement thereon in a manner which will be obvious and hence which need not be described nor illustrated.

In order to interchange the positions of the lower and upper holding frames, the manipulating mechanism later to be described is operated

to lower the upper holding frame 21 upon the lower holding frame 20 into the position indicated by the dash-dot lines of Fig. 1. It will be understood that the frame 20 is provided with pins 39 corresponding to the pins 35 in the upper frame but reversed in position. That is, the left pin 39 of the lower frame is arranged at the same distance to the left of the center of the standard 22 as is the right hand pin 35 of the upper frame; similarly, with the right hand pin 39 of the lower frame and the left hand pin 35 of the upper frame. 10

After the upper frame has been lowered as above described, onto the lower holding frame, the slide 32 is lowered as far as it will go on the standard 22, whereby the frame support 31 is removed from the pins 35 of the upper holding frame. In order, however, to provide sufficient clearance to permit the swinging of the holding frame, it is advisable to lower the frame support 20 still further. This is done by removing the wing screw 36 holding the support to the slide, whereby the support may be lowered relatively to the slide and the wing nut re-engaged with the lower hole. The holding frames may now be interchanged. This is done by removing a set of the bolts or screws 26 which enter the lower holding frame 20 and inserting said bolts or screws through the openings 40 of the bracket flange 25 and into the upper holding frame, leaving one 30 set of bolts in the lower holding frame until the upper frame has been properly secured at both ends to the flange 25. The remaining bolts 26 may now be removed from the lower frame and inserted into the proper openings 40 of the upper 35 frame.

The upper frame being thus secured to the bracket 23, and the lower frame being thus freed from said bracket, the locking pin 29 is removed as are the stops 28 and 30. The frame support 31 40 having been dropped sufficiently below the pins 39, the holding frames may now be swung as a unit about the pivot pins 24 to arrange the upper holding frame lowermost and the lower holding frame uppermost relatively to each other. 45 It will be understood that the pins 39 of the lower frame now assume the position formerly occupied by the pins 35 of the upper frame whereby the supporting arms 33 may be raised on upward movement of the slide so that said pins 50 39 enter the recesses 34 of the arms and the locking pin 29 and the stops 28 and 30 replaced.

On the upward movement of the slide 32, the holding frame, which is now uppermost, can be raised, leaving the holding frame which is now 55 lowermost in the position formerly occupied by the lower frame 20. It will be understood that the interchanging of the frames above described can be accomplished without the necessity for removing the frames from the apparatus and at 60 a minimum expenditure of time and labor.

The means for manipulating the slides 32 may take a variety of forms, some of which will now be described. As shown, said means comprises the rocking arm or lever 41 preferably H-shaped 65 in cross-section (Fig. 6) which is pivotally supported by the fulcrum pin 42 on the bracket 43, said pin being arranged nearer one end of the arm than the other. Said bracket is mounted on a suitable cross member 44 secured to and 70 bracing the standards 22.

The slides 32 are connected by suitable cables to the cable pin 45 carried by the bracket 46 arranged on and projecting over the end of the rocking arm. A pair of such cables 47 and 48 75

are provided, the upper ends of said cables being connected to the cable pin 45 and the other end of each of the respective cables being connected to one of the slides 32 as at a suitable pin 49 secured to the slide. The cable 47 passes about a pair of revoluble cable sheaves 50 and 51 and as has been indicated, is secured at its upper end to the cable pin 45. From the pin 49, the cable 48 first passes about the cable sheave 52 (Fig. 2) and then about the sheaves 53 and 54 and is similarly connected and secured at its upper end to the pin 45. It will be understood that the sheaves 50 and 53 are of the same diameter and are coaxially aligned (Fig. 1) and that the sheaves 51 and 54 are similarly of the same diameter and coaxially mounted.

A suitable bracket 55 secured to one of the standards 22 is employed to revolubly support the sheaves 50, 51, 53 and 54.

It will be seen that as the cable pin 45 is raised or lowered on the manipulation of the rocking lever 41, the upper ends of both cables 47 and 48 are raised or lowered precisely the same amount, and consequently raise or lower both slides 32 the same amount, whereby the holding frame carried by said slides is also raised and lowered the same amount at both ends thereof. It will further be understood that the weight of the upper holding frame and of the slides is transmitted through said cables to the cable pin and consequently, to the rocking lever, whereby when the rocking lever is swung in a counter-clockwise direction, the cables 47 and 48 are slackened and the frame 21 drops on the standards 22 by gravity though means for positively lowering the frame may be employed if desired, as will be obvious to those skilled in the art.

In order to overbalance said weight and to maintain the upper holding frame in the position into which it is moved by the manipulation of said rocking arm or lever, a counter weight 56 is slidably mounted on the rocking arm. To said counter weight is secured the safety stop 57 bent about the lower edge of the rocking arm and adapted to prevent vibration or displacement of the counter weight on the rocking arm. At its right end, the arm is provided with a suitable stop 58 of rubber or other suitable material adapted to engage the weight to limit the movement thereof toward the right, a similar stop 59 being arranged near the other end of said rocking arm to limit the movement of the counter weight toward the left. Depending flanges 60 on the weight arranged within the flanges of the H-shaped rocking arm serve to prevent side movement of the weight on said arm. At its right end, the counter weight is provided with a suitable projection 61 to which is secured one end of the weight operating cable 62.

Said cable passes over the sheave 63 revolubly mounted at the right end of the lever as by means of the bracket 64, and terminates in a weight or handle grip 71. Another section of the cable 62 similarly terminating in a hand grip 71 passes upwardly about a second upper sheave 67 (Fig. 4) in coaxial alignment with the upper sheave 63 and extends toward the left along the length of the rocking lever to the sheave 68 at the left end of the lever, said cable then passing back to and being connected to the left end of the counter weight as at 69. The sheave 68 is revolubly supported by a suitable bracket as 70 arranged near the left end of the rocking lever.

It will be seen that as one side or the other 75 of the cable 62 below the sheave 63 is pulled

downwardly by the operator, the counter weight 56 is moved along the rocking arm in the desired direction. If the cable is manipulated to move the counter weight toward the left from the position shown in Fig. 2, as said counter weight approaches the fulcrum pin 42, the weight of the upper holding frame and the parts connected thereto is balanced less and less, so that the rocking arm begins to drop under the unbalanced weight of the arm and the frame, thereby lowering the upper holding frame. As the counter weight moves past the fulcrum pin 42, the movement becomes more rapid.

In the dotted line position of the rocking arm shown in Fig. 2, the counter weight rests against the left stop 59, the upper holding frame has been lowered to rest on the lower holding frame and the slides 32 have been lowered along the standards 22 to the dotted line position of Fig. 1, wherein the supporting member 31 has been removed from the pins of the upper holding frame. It will be understood that when the cable 62 is operated in the opposite direction, the counter weight is drawn toward the right end of the lever until it engages the stop 58, thereby raising the slides 32 with comparatively little effort on the part of the operator.

Means are preferably provided for cushioning the last part of the rocking movement of the rocking arm in either direction. As illustrated, said means preferably takes the form of a pair of pneumatic stops 72 and 73 of any well known type and which therefore need not be described in detail. It need merely be said that the left stop 72 is adapted to engage an arm as 74 projecting from the bracket 70 to cushion the lowermost part of the downward movement of the left end of the rocking arm. Similarly, the pneumatic stop 73 is adapted to engage the arm 75 projecting from the rocking arm, on the last part of the downward movement of the right end of the rocking arm. Said stops 72 and 73 serve also to aid in overcoming the inertia of the rocking arm, the stop 72 aiding in the clockwise or frame raising movement and the stop 73 aiding in the frame lowering or counter-clockwise movement.

It will be understood that the fulcrum pin 42 is so arranged that when the counter weight is at the extreme right end of the rocking arm and adjacent the stop 58, considerable leverage is obtained, said leverage being sufficient to maintain the upper holding frame in its raised position.

As has been previously indicated, it is advisable to have the holding frames 20 and 21 interchangeable so that the blanket-holding frame may be arranged uppermost if desired. It therefore becomes advisable to provide a blanket which though flexible, is not likely to sag and which is so supported as to prevent side motion thereof when the holding frames are brought together, without danger of the negative or sensitized plates being moved from their correct positions. It will be understood that such movement would interfere with correct registry.

Referring to Figs. 7 and 8, I have there shown a comparatively rigid sheet 80 of composition board or the like supported in one of the frames as the frame 20, by means of a series of bent sheet springs 81, suitably secured on the four inner sides of the holding frame at spaced intervals and secured to the sheet 80.

Secured to the upper face of the sheet 80 but not to the blanket 86 in the position shown in Fig. 7 are a pair of spaced sections 82 and 83 of a

narrow strip of suitable durable and strong material. To form the space 84 between said sections, the intermediate section as 85 of the strip is secured to the under face of the blanket 86, 5 but not to the sheet 80. A plurality of strips are thus secured at spaced points of the area of the sheet 80 and thereby serve as a securing means for holding selected spaced points of the blanket to the comparatively rigid sheet 80. The 10 flexibility of the blanket is preserved by the yieldable springs 81 and the yieldability of the strips but undue movement of the blanket is prevented, since the blanket is compelled to carry the sheet 80 with it during its movement on the application 15 of vacuum to the holding frames, and complete flexibility of the blanket is nevertheless retained, permitting it to fit all the irregularities of the sensitized plate and to make intimate contact at all points. Should the frame 20 be 20 reversed in position so that the blanket 86 is uppermost instead of lowermost, then the blanket in its attempted movement attempts to carry with it the comparatively rigid sheet 80 whereby 25 its movement is restricted sufficiently to prevent the dangers above mentioned.

In the form of my invention shown in Figs. 9 and 10, an open network 87 of intersecting wires is held to the frame 20 as by means of the springs 86 each secured at one end to the network and 30 at the other end to the angle member 88, which is in turn attached to the inner face of the frame. It will be understood that one of such springs is preferably provided for each end of each of the wires. To secure the network to the blanket 86, 35 a series of suitable strips 90 are provided, said strips being secured and held in place by the wires of the network and being also secured to the under face of the blanket. It will be understood that the blanket is thus supported either 40 in its uppermost position or in its lowermost position in the frame against undue movement which might affect proper registry of the negative or of the sensitized plate or both.

In use, the upper holding frame 21 being in 45 its raised position as shown in Figs. 1 and 2, the sensitized plate is laid on the blanket 86 and the negative is then placed correctly on said sensitized surface. By now operating the cable 62, the counterweight 56 on the rocking arm 41 50 is moved toward the fulcrum 42. When said weight passes the fulcrum moving toward the stop 59, the upper holding frame 21 begins to drop by its own weight until it comes to rest on the lower holding frame 20. The rocking arm 41 at 55 the same time swings in a counter-clockwise direction, the last part of its movement being resisted by the engagement of the arm 74 with the stop 72. During this movement of the rocking arm or lever, the cables 47 and 48 are relaxed 60 whereby the weight of the frame acting through the supports 31 causes the slides 32 to move downwardly along the standards 22.

After the holding frames are brought together as above described, the vacuum may be applied 65 at the connection 91 (Fig. 2) to draw the blanket and the sensitized plate and negative carried thereby together into intimate contact. The blanket 86, however, while flexible, is sufficiently restricted in its movement to eliminate any danger 70 of relative movement of the negative and the sensitized surface. It will be understood that my invention is not necessarily limited to vacuum printing frames nor to printing frames only, but that contact between the sensitized surface and 75 the negative may be effected by any of the meth-

ods customary in the art, and that my invention may also be applied to the movement of the negative frames of photo composing machines by the proper arrangement of the lever, cables and negative frame.

After contact has been produced, the safety catches 92 on one of the holding frames are engaged with the pins 93 on the other holding frame to fasten the frames temporarily together. The thus locked frames may be swung into printing 10 position on the removal of the locking pin 29, it being understood that the supporting member 31 has been dropped down into substantially the dotted line position of Fig. 1 to become disengaged from the pins 39 of the lower frame when the 15 rocking arm 41 has been swung into the dotted line position of Fig. 2. The frames may now be swung about the pivot pins 24 into substantially vertical position wherein the lower holding frame engages the stop 30 and the printing operation 20 may proceed in the usual manner. After the printing is completed, the holding frames are 25 swung back to horizontal position, the lower frame being re-engaged with the stop 28 and the pin 29 re-inserted. By operation of the cable 62 in the 25 proper direction, the counterweight is now drawn toward the right along the rocking arm, and as it passes the fulcrum 42, the combined action of the counterweight and of the stop 72 begins to 30 swing the rocking arm in a clockwise direction, thereby to raise the upper holding frame. The sensitized surface and the negative carried by the lower frame may now be removed.

Should the blanket be arranged on the upper frame instead of on the lower frame, it will be 35 understood that the blanket is sufficiently supported by the supporting means shown in Figs. 7 to 10 inclusive to prevent displacement of the sensitized surface relatively to the negative positioned on the glass on the lower holding frame. 40

Referring now to that form of my invention shown in Figs. 12 and 13, I have there shown a modified form of the means for operating the rocking arm 41.

Said means takes the form of a standard chain 45 block 100 comprising the chain 101 and a pair of suitable chain-engaging sprocket wheels 102 and 103 secured respectively to the left end 104 of the rocking arm and to a suitable hook 105 at the lower part of the standard 22. The left end 106 50 of the rocking arm 41 carries a chain 107. Said chain 107 passes about the sprocket wheel 109, which is keyed to the shaft 110, said shaft being carried by a suitable bracket 111 on the standard 22. A freely mounted chain guard 112 serves to 55 maintain the chain 107 in place about the sprocket wheel 109. Said chain is carried upwardly and secured to the sprocket wheel 113 mounted on a suitable bracket carried by the member 44.

Secured to the shaft 110 for rotation therewith 60 are a pair of sprocket wheels 114, 115 of the same diameter and of greater diameter than the wheel 109. One chain 116 is secured to the sprocket wheel 114 and passes downwardly about the sprocket wheel 117 freely mounted on the stud 65 shaft 118, which shaft is in turn suitably supported as by the bracket 119 at the foot of the standard 22. The chain 116 is then brought upwardly from the sprocket wheel 117 to the pin 120 on the slide 32 to which the end of the chain 70 is secured.

A second chain 121 is similarly secured at one end to the sprocket wheel 115 (Figs. 13 and 16) passing thence towards the right about the loosely mounted sprocket wheel 122 to be secured to 75

the pin 123 on the right slide 32. It will be seen that rotation of the shaft 110 and consequent rotation of the sprocket wheels 114, 115 on said shaft moves the chains 116 and 121 precisely the same distance, in the same direction and consequently moves the slides 32 upwardly or downwardly the same amount to cause uniform movement at both ends of the upper holding frame 21.

Such rotation of the shaft 110 and of the sprocket wheels thereon is effected by suitable operation of the chain 101 of the chain block 100 to raise or lower the right end 104 of the rocking arm and thereby to lower or raise the left end 106 thereof and to release or tighten the chain 107. It will be understood that the distance through which the left end 106 of the rocking arm moves is less than the distance which the upper holding frame 21 moves during the same time, this being due to the difference in diameters of the sprocket wheels 109 and 114, 115.

The sprocket wheel 113, therefore, is made of sufficient diameter to take about its circumference, a length of the chain 107 equal to the greatest distance through which said left end 106 of the rocking arm may move. A torsion spring 124 acting between the collar 125, on the shaft 126 on which said sprocket wheel 113 is mounted, and the hub of said sprocket wheel provides a spring take-up for the chain 107 to maintain said chain taut at all times.

By means of the reduction sprocket wheels 109, 114, 115, the angle through which the rocking arm 41 must move in order to raise and lower the upper holding frame may be substantially reduced, thereby making it possible to produce an apparatus of minimum height when desired to do so. The chain block 100 makes it possible to operate the frame moving mechanism with comparatively little effort, providing a sufficient mechanical advantage for that purpose.

Referring now to Fig. 14, I have there shown a simple means for operating the rocking arm 41 in cases where low cost of the apparatus is a determining factor. In this form of my invention, a rope or cable 127 is secured to the left end 104 of the rocking arm, the other end of the rope being adapted to be secured to the hook 105 arranged at the foot of one of the standards 22, after the lever has been manipulated as desired.

In Fig. 15, I have shown a modified form of the means for slidably supporting the counter weight 56 of Figs. 1, 2, 4, 5 and 6. In this form of my invention, the bracket 128 for supporting the wheel 63 is offset in such a manner that the counter weight may pass to the extreme end of the rocking arm 41. The stop 129 is made at said extreme end and replaces the stop 58 of Fig. 2. The cable 62 is secured to the counter weight near its front end as at 130 to shorten the over-all length of the rocking arm. In Fig. 15, I have further shown means for reducing the resistance to the movement of the counter weight 56 along the arm 41. Said means takes the form of suitable rollers 131 revolvably mounted on pins 132 on the counter weight and rolling on tracks 113, preferably made integral with the rocking arm.

It will be understood that the flexible connections between the rocking arm and the frame slides may be considerably varied to conform to various types of printing frames and photo composing machines or the like. Further, if desired, the weight of the holding frame and of the parts connected thereto may be counterbalanced by a counter weight arranged in any

desired position to reduce the power required to swing the lever.

It will be seen that I have provided means for operating the holding frames of printing apparatus rapidly and at low cost, for interchanging the frames, for insuring against undesirable movement of the blanket thereof, and adapted to meet the severe requirements of practical use.

While I have shown and described certain specific embodiments of my invention, I do not wish to be understood as limiting myself thereto, but intend to claim my invention as broadly as may be permitted by the state of the prior art and the scope of the appended claims.

I claim:

1. In a photographic printing apparatus, a pair of separable holding frames, a lever pivoted on a horizontal axis in spaced relation to the frames, and means operatively connecting the lever to one of the frames for raising and lowering said frame on the swinging of the lever, said means transmitting the weight of said frame to one end of the lever.

2. In a photographic printing apparatus, a pair of separable holding frames, a pivotally mounted lever, and means for separating said frames on the swinging of the lever in a given direction including flexible connections between said lever and one of the frames, said connections being tensioned on the swinging of the lever in one direction to transmit the weight of said frame to the lever, and said connections being slackened on the swinging of the lever in the other direction to permit said frame to drop by gravity.

3. In a photographic printing apparatus, a pair of separable holding frames, a lever, means operatively connected to the lever for raising and lowering one of said frames on the operation of said lever, and cushioning means arranged in the path of said lever to resist the last part of the movement of said lever and to support the lever.

4. In a photographic printing apparatus including a frame, a swingable lever carrying the weight of said frame, and means including a movable weight operatively connected to the lever for swinging the lever to raise and lower said frame.

5. In a photographic printing apparatus including a frame, a swingable lever carrying the weight of said frame, means operatively connected to the lever for swinging the lever to raise and lower said frame, and air cushioning means arranged in the path of said lever.

6. In a photographic printing apparatus including a frame, a lever operatively connected to the frame, a weight movable relatively to the frame, and means for manipulating the weight for swinging the lever.

7. In a photographic printing apparatus including a frame, means for moving said frame comprising a lever, and a movable operating weight for the lever.

8. In a photographic printing apparatus, a frame, means for slidably supporting the frame for vertical movement, a lever supporting the weight of the frame, a flexible member connecting the frame to one end of the lever, and means including a second flexible member at the other end of the lever for swinging the lever and thereby adjusting the vertical position of the frame.

9. In a photographic printing apparatus, a pair of holding frames, means retractable below the lowermost frame for supporting the uppermost frame, means on the frames for selectively en-

gaging the retractable means, a fixed pivot, means for operatively connecting the pivot to the lowermost frame and also to the uppermost frame when the uppermost frame rests on the lowermost frame, and lever means for raising and lowering the uppermost frame when the pivot connecting means is disconnected therefrom.

10. In a photographic printing apparatus, a pair of holding frames, means for pivotally supporting one of said frames, means for slidably supporting the other frame for movement toward and from said one frame, and means for removably holding said frames together for pivotal movement as a unit about said pivotal supporting means whereby the relative positions of said frames may be reversed, said pivotal supporting means comprising a plate of a height substantially equal to the combined heights of said frames, a pivot pin projecting from the plate and 20 removable fastening means passing through the plate and adapted to enter the frames.

11. In a photographic printing apparatus provided with a pair of cooperating holding frames, an upright slide support at each end of the frames, a slide on each support, means on the slides for supporting the uppermost one of the frames only, said means being retractable out of engagement with the uppermost frame when said uppermost frame rests on the lower frame, and 30 means operatively connected to the slides for raising and lowering said slides and thereby correspondingly moving one of the frames.

12. In a photographic printing apparatus provided with a pair of cooperating frames, an upright slide support at each end of the frames, a slide on each support, and a frame supporting member on each of the slides adapted to engage and support the uppermost of the frames only, said member being retractable out of engagement with the uppermost frame when said uppermost frame rests on the lower frame.

13. In a photographic printing apparatus provided with a pair of cooperating frames, an upright slide support at each end of the frames, a slide on each support, a frame supporting member on each slide movable below the lowermost of the frames, and means on the frames for selectively engaging the frame supporting member to support one of the frames only when said one frame is in a position above the other frame.

14. In a photographic printing apparatus provided with a pair of cooperating frames, means for pivotally supporting one of the frames, and movable means, disconnectable from and retractable below both of said frames, for normally sup-

porting the other of the frames for vertical movement therewith.

15. In a photographic printing apparatus, a holding frame, means for slidably supporting the frame for vertical movement, and means for moving said frame including a pivoted lever, a flexible member operatively connected at one end to the frame, and at its other end to the lever, and a revoluble wheel interposed between the lever and the frame and engaging the member and changing the direction of movement thereof.

16. In a photographic printing apparatus, a holding frame, means for slidably supporting the frame for vertical movement, and movable means for normally sustaining the weight of the frame and for determining the vertical position thereof in the apparatus, said movable means comprising a lever extending across the apparatus, and flexible means connecting an end of the lever to the supporting means whereby movement of the lever in a direction to slacken the flexible means releases the frame to drop by gravity.

17. In a photographic printing apparatus, a holding frame, means for supporting the frame for vertical movement comprising a pair of spaced uprights, a slide on each of the uprights, a supporting member adjustably carried by each of the slides, projecting pins on the frame adapted normally to be engaged by the supporting member to support the frame when the frame is otherwise unsupported and to be disengaged from the supporting member when the frame is otherwise supported, a lever arranged above the frame and pivoted intermediate its ends, flexible members connecting the lever and the slides, and means including a flexible member held by the lever for swinging said lever in a given direction to raise the frame and to swing the lever in the opposite direction to slacken said flexible connecting member and thereby to permit the slides and the frame to drop by gravity.

18. In a photographic printing apparatus, a pair of frames, a support adapted to engage and support the uppermost of the frames only, said support being retractable out of engagement with the uppermost frame when said uppermost frame rests on the lowermost frame, means on the frames for selectively engaging the support to support one of the frames only, a pivot, and means removably securable to both of said frames for supporting the pivot centrally of both of said frames when the uppermost frame rests on the lowermost frame.
